UNITED STATES PATENT OFFICE.

JAKOB TRIEM, OF FRANKFORT-ON-THE-MAIN, GERMANY, ASSIGNOR TO UNITED SHOE MACHINERY COMPANY, OF PATERSON, NEW JERSEY, A CORPORATION OF NEW JERSEY.

MACHINE FOR OPERATING UPON THE SOLES OF BOOTS AND SHOES.

1,161,086.

Specification of Letters Patent. Patented Nov. 23, 1915.

Application filed September 25, 1912. Serial No. 722,275.

To all whom it may concern:

Be it known that I, JAKOB TRIEM, a subject of the King of Bavaria, residing at Frankfort-on-the-Main, in the Kingdom of Prussia and Empire of Germany, have invented certain Improvements in Machines for Operating Upon the Soles of Boots and Shoes, of which the following description, in connection with the accompanying drawings, is a specification, like reference characters on the drawings indicating like parts in the several figures.

This invention relates to machines for operating on soles of boots and shoes, hereinafter referred to generically as "shoes", and primarily to a machine for closing a channel in the tread face of a sole and also preferably for consolidating the marginal portion of the sole.

The machine hereinafter described is more particularly designed for use in the manufacture of shoes, the soles of which are provided with what is known as an "English channel" or a channel formed as a slit which is cut at a comparatively large angle to the tread face, approximating a right angle. As herein employed, the term "sole" is used in its generic sense to include not only the single sole of the usual McKay, pegged or nailed shoe but also a double or tapped sole and the combined welt and outsole of a welt shoe.

Various operations performed upon a shoe during the process of manufacture tend to separate the walls of the slit or channel in the tread face wherein the outseam lies. For example, during the leveling operation, the margin of the sole is forced toward the upper of the shoe, thus tending to open the channel. However, in order that the finished shoe may have its maximum marketable value, it is important that the channel shall be tightly closed and be as nearly invisible as possible.

Accordingly, the principal object of this invention is to provide novel and effective means for closing the channel and preferably for consolidating and finishing the edge of the sole at the same time.

With this object in view, one feature of the invention comprises the provision of a pair of rotary tools located one within the other and constructed and arranged to act respectively upon the edge and upon the

tread face of the sole, together with means for imparting rotary movements in opposite directions to the tools. In the illustrated embodiment of the invention, the tools are located concentrically, one tool being shaped and operated to close the channel in the face of the sole and the other to beat or pound the edge of the sole and thus assist also in closing the channel, in addition to consolidating and finishing the sole edge. Preferably, each of the two tools is cylindrical in form and is provided with spaced teeth at one end which constitute the active elements of the tool.

In addition to the features above specifically referred to, the invention comprises also certain other combinations and arrangements of parts and features of construction which will now be described in detail and which will be defined in the appended claims.

Referring to the accompanying drawings, Figure 1 is a side elevation, partly in section, of the head of a machine embodying the invention in its preferred form; Fig. 2 is a similar view upon a larger scale of the channel closing tool; Fig. 3 is a still larger detail view of one of the teeth of the channel closing tool; and Figs. 4 and 5 are end and side elevations respectively of the edge beating tool.

As illustrated, the head 2 of the machine supports in suitable bearings a hollow shaft 4 and a concentrically arranged inner shaft 6. The channel closing tool 8 is mounted upon the shaft 4 so as to be slidable axially thereon but it is compelled to rotate with the shaft by means of a spline 9 fixed to the shaft and provided with an outturned end 10 which extends into a keyway 11 in the tool 8. The end 10 of the spline not only causes the tool 8 to rotate positively with shaft 4 but it also prevents the tool from sliding off the end of the shaft. A spring 12 surrounding the shaft and interposed between the rear end of the tool and a collar 14 fixed to the shaft tends constantly to maintain the tool in its extreme outer position.

The outer end of the tool 8 is formed with a series of spaced teeth 16, the ends 18 of which are constructed and arranged to wipe over the tread face of the sole during the rotation of the tool so as to close the chan-

nel. As clearly illustrated in Figs. 2 and 3, the faces 18 are beveled in two directions. They lie approximately in a conical surface the axis of which is the axis of the tool 8, thus being beveled to correspond substantially with the transverse curvature of the sole B of the shoe A, as shown in Fig. 1. The faces 18 are also slightly beveled approximately in the direction of rotation of the tool so that an increasing pressure will be exerted upon the sole adjacent the channel C as each tooth travels over the sole.

Arranged concentrically with tool 8 and fixed to the inner shaft 6 is the edge beating tool 22 which is also provided with teeth 24 which project outwardly beyond the teeth 16 of the tool 8. The teeth 24 are so spaced that in the rotation of the tool a rapid succession of blows is imparted to the edge of the sole which not only assist in closing the channel but also finish and consolidate the sole edge, making it smooth, hard and regular in shape. The two shafts and the two tools carried respectively thereby are rotated independently and diversely through the pulleys 26 and 28. Preferably the tools are rotated in opposite directions, causing the machine to run with less vibration and resulting in a more effective operation upon the sole.

A rest for the tread face of the sole is provided in the form of a freely rotatable roll 30 mounted upon a spindle 32 fixed in an arm 34. By means of a bolt 36 passing through arm 34 and through an elongated slot 38 in a bracket 40, the arm, and therefore the roll 30, may be clamped to the bracket after it has been adjusted vertically and angularly as desired. Conveniently, the angular adjustment may be secured by a set screw 42 threaded through a lug 44 upon the arm and impinging against the lower surface of the bracket 40. This bracket is mounted to slide horizontally in a guideway 45 in the frame 2 and can be secured in adjusted position by a set screw 46.

The manner in which the machine may be used in operating upon the sole B of a shoe A for the purpose described will be readily understood from the foregoing description read in connection with the accompanying drawings. The sole rest 30 is adjusted to support the sole of the shoe in proper relation to the teeth of the two tools 8 and 22. The operator, holding the shoe in his hands, presses the sole inwardly and upwardly against the teeth of the tools, as shown in Fig. 1, compressing the spring 12. He then feeds the shoe along so as to present the desired portions of the sole progressively to the tools, with the result that as the tools are rotated in opposite directions the ends 18 of teeth 16 wipe over and beat the tread face of the sole to close the channel while 65 the cylindrical surfaces of teeth 24 force

together the walls of the channel and also consolidate and finish the sole edge.

Having thus indicated the nature and scope of the invention and having described in detail a machine embodying the invention in a preferred form, what I claim as new and desire to secure by Letters Patent of the United States is:—

1. A machine of the class described, comprising a pair of rotary tools located one within the other and arranged and shaped to beat the edge of the sole of a shoe and close the channel in the tread face.

2. A machine of the class described, comprising a pair of rotary tools located one within the other and constructed and arranged to act respectively upon the edge and upon the tread face of the sole of a shoe, in combination with means for rotating said tools simultaneously in opposite directions.

3. A machine of the class described, comprising a pair of concentric cylindrical tools, one end of each of which is provided with spaced teeth, the outer cylindrical surfaces of the teeth of one tool being arranged and shaped to beat the edge of the sole of a shoe while the ends of the teeth of the other tool are arranged and shaped to wipe over the tread face of the sole and close the channel.

4. A machine of the class described, comprising a pair of concentric tools provided with teeth having open spaces between them, the surfaces of the teeth of one tool being arranged and shaped to beat the edge of the sole of a shoe while the ends of the teeth of the other tool are arranged and shaped to wipe over the tread face of the sole and close the channel, in combination with means for rotating said tools simultaneously in opposite directions and an angularly adjustable rest for said tread face constructed and arranged to position the sole in proper operative relation to the tools.

5. A rotary cylindrical channel closing tool provided at its outer end with spaced teeth (16), having relatively deep slots between them open at each end, the end faces (18) of which teeth lie approximately although not exactly in a single conical surface, the axis of which is the axis of the tool, but which are slightly beveled in the general direction of rotation of the tool.

6. A machine of the class described, comprising a pair of independently rotated concentric tools respectively shaped and operated to beat the edge of the sole of a shoe and to close the channel in its tread face, one end of each tool being provided with spaced teeth, the faces of the teeth of one tool being arranged and shaped to beat the edge of the sole of a shoe while the ends of the teeth of the other tool are arranged and shaped to wipe over and close the channel in its tread face, the acting ends of the

channel closing tool lying approximately in a single conical surface but being slightly beveled.

7. A machine of the class described, comprising a pair of concentric shafts and independent means for rotating them, in combination with a pair of tools mounted respectively on said shafts and shaped and operated to beat the edge of the sole of a 10 shoe and close the channel in its tread face.

8. A machine of the class described, comprising a pair of concentric shafts and independent means for rotating them, in combination with a pair of tools mounted re-

spectively on said shafts and shaped and 15 operated to beat the edge of the sole of a shoe and close the channel in its tread face, together with a spring for supporting one of the tools yieldingly in the direction of its axis and an adjustable rest for the tread 20 face of the sole.

In testimony whereof I have signed my name to this specification in the presence of two subscribing witnesses.

JAKOB TRIEM.
